UNITED STATES PATENT OFFICE.

GEORGE TRENCH, OF SAN FRANCISCO, CALIFORNIA, ASSIGNOR TO THE
TONITE POWDER COMPANY, OF SAME PLACE.

MACHINE FOR MAKING BLASTING-CARTRIDGES.

SPECIFICATION forming part of Letters Patent No. 245,031, dated August 2, 1881.

Application filed April 14, 1881. (No model.)

To all whom it may concern:

Be it known that I, GEORGE TRENCH, of the city and county of San Francisco, State of California, have invented an Improvement 5 in Machines for the Manufacture of Blasting-Charges; and I hereby declare the following to be a full, clear, and exact description thereof.

My invention relates to an improvement in the manufacture of blasting-charges, and it relates 10 more particularly to the mechanical method of making the charge of the desired form and compactness, and to the machinery for accomplishing this result.

In the manufacture of blasting-charges which 15 consist of crushed or pulped gun-cotton mixed with any of the nitrates it is necessary to submit each charge to a heavy pressure and form it into cylinders of high density, and some of said cylinders must be perforated with holes 20 to receive the safety-fuse and detonator by which the charge is exploded. This treatment is necessary in order to produce the best results in mining, and my invention is designed to provide a machine by which the charges are 25 properly compacted and perforated.

Referring to the accompanying drawings for a more complete explanation of my invention, Figure 1 is a vertical section of my apparatus. Fig. 2 is a front view. Fig. 3 is a perspective 30 view, showing the revolving table and plungers.

A is a vertical frame having supported in boxes across its top the crank-shaft B. This shaft may have a spur-wheel, C, at one end, to 35 be driven by a pinion, D, upon the shaft E, or it may be driven by other suitable connections which will furnish sufficient power. At the opposite end of this shaft B is a crank, F, which operates the vertically-moving slide G through 40 a connecting-rod, H. This slide carries the pressing-tool I, which is secured to it in any suitable manner. Below this slide, with its tool, is a circular table, J, which is mounted upon a vertical central spindle, about which it turns, 45 the outer lower edge of the table moving upon a strong support, P, by which the pressure of the tool is resisted, and upon which the base of the charge is supported while it is being compressed. Around the periphery of the table 50 are formed vertical holes α , into which the powder-charges are placed, so that as the table is turned the charges will be brought successively beneath the pressing-tool, which is forced down upon them, thus producing the

high density which is necessary. In order to 55 form chambers or openings within these compressed powder-charges, so that the fuse and detonator may be properly introduced, I form the pressing-tool with a slender elongated point, K, which enters the end of the charge as the 60 tool descends, and thus forms the hole, the charge being forcibly compressed around it. Another tool or punch, L, is connected with the slide G at a distance from the pressing-tool I equal to the distance between the holes α in 65 the table, and after a charge has been compressed the next movement of the table brings it beneath the punch L, by which it is forced out, the holes in the table extending entirely through it, and the space beneath being open 70 at this point to allow the finished charge to escape.

The table is rotated upon its axis by means of a pawl, M, which is formed to fit the teeth N of a circular rack upon the periphery of the 75 table. This pawl is pivoted to the lower end of an arm, O, which extends to the upper part of the frame A, and is pivoted at its center, so as to be oscillated by the action of the crank-arm, or a cam or eccentric upon the shaft, as it 80 revolves. This forces the pawl forward, and thus moves the table one tooth corresponding with the distance between the molding-holes. By this means each hole passes in rotation under the pressing-tool, and the powder loaded 85 into the holes is thus pressed into a smaller compass and given the solid form required for a charge, while the second tool forces the completed charge out of the molding-holes as they arrive beneath it, so that they will fall into a 90 receiver below.

Having thus described my invention, what I claim as new, and desire to secure by Letters Patent, is—

The rotating table J, with the molding-holes 95 α and the support P beneath, in combination with the vertically-moving slide having the pressing-tool I and the ejecting tool or punch L acting simultaneously upon the charges in adjacent holes, substantially as herein described.

In witness whereof I have hereunto set my hand.

GEORGE TRENCH.
